UNITED STATES PATENT OFFICE

142,173

DESIGN FOR A PORTABLE TAPE MOISTENING DEVICE OR THE LIKE

Walton C. Marsh, Belleville, Ill., assignor to Marsh Stencil Machine Company, Belleville, Ill., a corporation of Illinois

Application January 5, 1945, Serial No. 117,272

Term of patent 14 years

(Cl. D74—10)

To all whom it may concern:

Be it known that the undersigned, Walton C. Marsh, a citizen of the United States, residing at Belleville, Illinois, has invented a new, original, and ornamental Design for a Portable Tape Moistening Device or the like, of which the following is a specification, reference being had to the accompanying drawing forming a part thereof, in which:

Fig. 1 is a perspective view of a portable tape moistening device embodying the instant design viewing the device from its tape dispensing end and showing one of its sides; and

Fig. 2 is a similar view showing an opposite side of the device.

The dominant features of the invention are those parts shown in full lines.

I claim:

The ornamental design for a portable tape moistening device or the like, substantially as shown and described.

WALTON C. MARSH.
